RAILWAY TRAFFIC CONTROLLING
APPARATUS

Harry C. Vantassel, Swissvale, Pa., assignor to
The Union Switch & Signal Company, Swiss-
vale, Pa., a corporation of Pennsylvania

Application June 22, 1935, Serial No. 27,878

11 Claims. (Cl. 246—3)

My invention relates to railway traffic controlling apparatus. More specifically, my invention relates to signaling apparatus for stretches of single track between passing sidings. One feature of my invention is the provision of means for enforcing a time interval spacing between trains moving in the same direction over such stretches of single track. Although my invention is particularly adapted for use with the well-known "manual block" system of signaling, it is not necessarily so limited.

I will describe one form of apparatus embodying my invention, and will then point out the novel features thereof in claims.

In the accompanying drawing, Fig. 1 is a diagrammatic view illustrating a track layout including switches and signals to which my invention may be applied. Fig. 1 also illustrates the track relays and the traffic relays for the layout as well as a pair of switch indicating relays associated with switch 2 and an approach locking relay associated with the signals located at switch 6. Fig. 2 is a diagrammatic view illustrating the circuits for the control of the approach locking relays and a time element relay with its repeating relay all associated with the group of signals located at switch 2. Fig. 3 is a diagrammatic view illustrating the control circuits for a stick relay R2S cooperating with the circuits shown in Figs. 1, 2 and 4. Fig. 4 is a diagrammatic view illustrating the signal network for controlling the group of signals associated with switch 2.

Similar reference characters refer to similar parts in each of the several views.

In order to simplify the drawing, the relay contacts are not, in all instances, shown directly beneath the relay which actuates such contacts. Each such contact, however, is provided with the same reference character which identifies the actuating relay, plus a distinguishing numeral.

Referring first to Fig. 1, the reference character X designates a stretch of single track divided by means of insulated joints 3 into a plurality of sections designated by the reference characters 1T, 2T, 3T, etc. Each section is provided with a track circuit including a track relay designated by the reference character R with a suitable prefix, connected across the rails at one end of the section and a track battery 4 connected across the rails at the other end of the section. The section 2T contains a track switch designated by the reference character 2 which switch, as here shown, connects a passing siding Y with the stretch of track X. Likewise, the section 6T contains a track switch designated by

the reference character 6 which switch, as here shown, connects a passing siding Z with the stretch of track X. The stretch of track between the switches 2 and 6 is commonly known as a manual block section. 5

The switch 2 is operated by a mechanism 2M which is controlled by an operator at a point remote from the switch in any suitable and well-known manner not shown in the drawing. Similarly, the switch 6 is operated by a mechanism 6M which is controlled by the operator at a remote point in a manner similar to that provided for mechanism 2M. The switch 2 governs a contact 10 in accordance with the switch position by any usual and well-known means. 15

The reference characters 2NK and 2RK designate a pair of switch indicating relays controlled by the contact 10. As here shown, the relay 2NK will be energized only if the switch 2 is in its normal position in which it is illustrated, and the relay 2RK will be energized only if the switch 2 is in its reverse position. 20

The reference characters LA2 and LB2 designate two indicating units of a signal which governs westbound traffic over the switch 2. The unit LA2 governs traffic over the switch in its normal position and unit LB2 governs traffic over the switch in its reverse position. The reference characters RA2 and RB2 designate two indicating units of a signal for governing eastbound traffic over the switch 2 in its normal position and the reference characters RC2 and RD2 designate two indicating units of a signal for governing eastbound traffic from siding Y over the switch 2 in its reverse position. The 25 reference characters RA2 and RC2 govern the movement of traffic into the manual block section when such section is unoccupied, and the units RB2 and RD2 govern the movement of traffic into the manual block section when the section is already occupied by eastbound traffic. Usually, the indication displayed by signals RA2 and RC2 for permitting train movements into the manual block section will be different and distinct from the indication displayed by the signals RB2 and RD2 so that an engineman in accepting these signals will be informed as to whether he is entering an unoccupied block or is following a preceding train. 30

The reference characters RA6 and RB6 designate two units of a signal for governing eastbound traffic over the switch 6 and the reference characters LA6, LB6, LC6 and LD6 designate the units of signals for governing westbound traffic over the switch 6. The signals associated 35

with the switch 6 operate in a manner similar to that just described for the corresponding signals associated with the switch 2.

The reference character L6FR designates a traffic relay for controlling the signals LA6, LB6, LC6 and LD6. The relay L6FR is controlled by the track relays 3R, 4R, and 5R, and by the approach locking relay R2MR. The reference character R2FR designates a traffic relay for controlling signals RA2, RB2, RC2 and RD2. The relay R2FR is controlled by the track relays 3R, 4R and 5R and by an approach locking relay L6MR. The control circuits for the relay L6MR, although not shown in the drawing, are similar to those provided for the approach locking relay R2MR which will be explained more in detail hereinafter.

Referring now to Fig. 2, the reference character 2TE designates a timing device or time element relay, here shown as a relay having a slow pick-up characteristic. The time element relay 2TE is provided with a contact 11 (see Fig. 4) which is closed only when the relay 2TE is in its initial deenergized condition, and with contacts 12, 13, and 14 which are closed only when the relay 2TE completes its operation a predetermined time interval after being energized. The reference character 2TEP designates a relay having a slow release characteristic, which relay 30 repeats the time element of relay 2TE.

The reference characters R2MR and L2MR designate approach locking relays for eastbound and westbound traffic, respectively, over the switch 2. The relays R2MR and L2MR, as will 35 be explained more in detail hereinafter, prevent operation of the associated signals under certain dangerous traffic conditions.

Referring now to Fig. 3, the reference character R2S designates a stick relay having a slow 40 release characteristic. The relay R2S is effective, at times, to place the time element relay 2TE under the control of the approach locking relays R2MR and L2MR, or under the control of the traffic relay R2FR, depending upon traffic conditions.

Referring to Fig. 4, the reference characters R2HS and L2HS designate a pair of directional relays which are controlled from a remote point in any suitable and well-known manner. The 50 relay R2HS controls signal control relays RA2H, RB2H, RC2H and RD2H by means of the illustrated signal network for governing eastbound traffic over the switch 2; and relay L2HS controls signal control relays LA2H and LB2H for 55 governing westbound traffic over the switch 2. It will be noted that the signal control relays RA2H and RC2H have a slow release characteristic. As will be explained more in detail hereinafter, this slow release characteristic provides 60 for the proper operation of the relay R2S.

The reference characters B and C in all views designate the positive and negative terminals, respectively, of a suitable source of current not shown in the drawing.

Having thus described in a general manner the 65 various parts of the apparatus embodying my invention, I will now explain the operation of the system as a whole.

I shall first assume that with all apparatus 70 in the normal condition in which it is shown in the drawing, the operator at the remote point wishes to clear signal RA2 to permit an eastbound train to enter the manual block section. He will accomplish this by energizing the directional relay R2HS (see Fig. 4) in any suit-

able and well-known manner not shown in the drawing. When relay R2HS is energized, the relay RA2H will be energized over a circuit which passes from terminal B through front contact 15 of relay L2MR, back point of contact 16 of relay L2HS, contact 11 of relay 2TE, contact 17 of track relay 2R, front point of contact 18 of relay R2HS, front contact 19 of relay 2NK, front point of contact 20 of relay R2FR, and relay RA2H, to terminal C. When the relay 10 RA2H becomes picked up, the signal RA2 will be caused to indicate proceed by means not shown in the drawing. The picking up of relay RA2H also causes the eastbound approach locking relay R2MR to become deenergized by the 15 opening of a circuit (see Fig. 2) which passes from terminal B through back contact 21 of the relay RA2H, back contact 22 of relay RB2H, back contact 23 of relay RC2H, back contact 24 of relay RD2H, front contact 25 of relay 4R, 20 front contact 26 of relay 2NK, and relay R2MR to terminal C. When relay R2MR is released, the westbound traffic relay L6FR associated with the group of signals at switch 6 will also become released by the opening of a circuit (see 25 Fig. 1) which passes from terminal B through front contact 27 of relay R2MR, front contact 28 of relay 3R, front contact 29 of relay 4R, front contact 30 of relay 5R, and relay L6FR, to terminal C. When the relay L6FR is released, 30 the opposing signals LA6, LB6, LC6 and LD6 can not be caused to indicate "proceed" since these signals are controlled by the relay L6FR in such a manner that these signals can be cleared only if relay L6FR is energized.

When the train passes signal RA2 and enters section 2T, the track relay 2R will become released. When this occurs, a pick-up circuit (see Fig. 3) will be closed for relay R2S which circuit passes from terminal B through the front point of contact 31 of relay R2FR, back contact 32 of track relay 2R, back point of contact 33 of relay RC2H, front point of contact 34 of relay RA2H, and relay R2S, to terminal C. It will be noted that when relay 2R is released, the signal control relay RA2H will be deenergized by the opening of front contact 17 in the control circuit for this relay. Since, however, relay RA2H has a slow releasing characteristic, the pick-up circuit just described for relay R2S will become closed prior to such time as relay RA2H reaches its released condition. In the meantime, the picking up of the relay R2S will close a stick circuit which passes from terminal B through front point of contact 31 of relay R2FR, back contact 32 of relay 2R, wire 46, front contact 35 of relay R2S, and relay R2S, to terminal C, so that relay R2S will be maintained in its picked-up condition even after its pick-up circuit is opened.

When the train enters section 3T, so that track relay 3R becomes released, the traffic relay R2FR will also become released, as will be apparent from an inspection of Fig. 1. When relay R2FR is released the relay R2S will be energized by another stick circuit which passes from terminal B through back point of contact 31 of relay R2FR, back point of contact 34 of relay RA2H, back point of contact 33 of relay RC2H, wire 46, front contact 35 of relay R2S, and relay R2S, to terminal C. Since relay R2S has a slow release characteristic, this relay will be maintained in its picked-up condition while being transferred from one stick circuit to another.

When the train vacates section 2T so that track relay 2R again becomes picked up, the operation 75

of the time element relay 2TE will be initiated by the closing of a circuit (see Fig. 2) which passes from terminal B through back contact 21 of relay RA2H, back contact 22 of relay RB2H, back contact 23 of relay RC2H, back contact 24 of relay RD2H, back contact 36 of relay R2FR, front contact 37 of relay 2R, front point of contact 38 of relay R2S, back contact 39 of relay 2TEP, and relay 2TE, to terminal C. When relay 2TE completes its operation at the expiration of a given time interval which usually will be regulated in accordance with the operating rules governing the manual block system, the relay 2TEP will become energized by a circuit which passes over the same 10 path as just described for the relay 2TE up to and including front point of contact 38 of relay R2S, and thence over contact 14 of the relay 2TE, to relay 2TEP and terminal C. When relay 2TEP is energized, it will be maintained in that 15 condition by a stick circuit which passes over the same path as the pick-up circuit just described except that front contact 40 of relay 2TEP is substituted for contact 14 of relay 2TE. When the relay 2TEP becomes energized, the relay 2TE will 20 become deenergized due to the opening of back contact 39 of relay 2TEP, and will return to its initial condition. The relay 2TEP has a slow release characteristic so that it will remain in the picked-up condition while its control is being 25 transferred from the pick-up circuit to the stick circuit.

If, when the relay 2TEP is energized, the operator at the remote point wishes to permit another eastbound train to enter the manual block 30 section while the first train is still occupying the block, he may do so by again energizing relay R2HS. If relay R2HS is already in its picked-up condition, the proper signal to permit such a train movement will be displayed automatically. Since 35 relay R2S and relay 2TEP are both energized, a pick-up circuit will be closed so that relay RB2H will also be energized and will thus cause signal RB2 to display, by means not shown in the drawing, a "proceed" indication permitting the 40 second train to enter the manual block section. This pick-up circuit for relay RB2H (see Fig. 4) passes over the same path as the circuit previously traced for relay RA2H up to and including front contact 19 of relay 2NK and thence over the back 45 point of contact 20 of relay R2FR, front contact 41 of relay R2S, front contact 42 of relay 2TEP, and relay RB2H to terminal C. It will be noted that when the signal control relay RB2H is picked up, the relay 2TEP will be released due to the opening 50 of back contact 22 of relay RB2H (see Fig. 2) which will, in turn, open the pick-up circuit for the relay RB2H at front contact 42 of relay 2TEP. The relay RB2H, however, will be maintained in its picked-up condition by virtue of a stick circuit 55 which passes from terminal B over the same path as just described for its pick-up circuit up to and including the back point of contact 20 of relay R2FR, and thence over front contact 43 of relay RB2H, and relay RB2H, to terminal C.

60 When the second train enters section 2T so that relay 2R becomes released, the relay RB2H will become released and signal RB2 will again indicate stop. When the second train vacates section 2T so that relay 2R again becomes energized, the operation of the time element relay 2TE will be initiated again since the relay R2FR will remain deenergized as long as the manual block section is occupied, and relay R2S will remain energized as long as relay R2FR remains deenergized. Thus, 65 it will be apparent that the apparatus embodying 70

my invention provides means for permitting trains moving in the same direction to follow one another into the manual block section a measured time interval apart but prevents an opposing train from entering the block while occupied. 5

It will be observed that the time element relay 2TE is employed not only for providing a time interval for the spacing of the trains but also for the release of the approach locking in the usual and well-known manner. For example, if 10 signal control relay RA2H is energized while approach section 1T is occupied, it will be observed that approach locking relay R2MR will become deenergized and may be energized again only if track relay 2R is released or if relay 2TE completes its operation provided relay RA2H is restored to its released condition. After relay 15 R2MR is released by the energization of relay RA2H, the operation of the relay 2TE will be initiated when relay RA2H is restored to its initial condition, by the closing of a circuit which passes from terminal B through back contact 21 of relay RA2H, back contact 22 of relay RB2H, back contact 23 of relay RC2H, back contact 24 of relay RD2H, back point of contact 44 of relay 20 R2MR, front point of contact 45 of relay L2MR, back point of contact 38 of relay R2S, back contact 39 of relay 2TEP, and relay 2TE, to terminal C. When relay 2TE completes its operation 25 at the expiration of the given time interval, the relay R2MR will become energized over a pick-up circuit which passes over back contacts 21, 22, 23 and 24 of signal control relays RA2H, RB2H, RC2H and RD2H, respectively, and thence over front contact 12 of relay 2TE, to relay R2MR. 30 When relay R2MR is picked up, the approach locking will be released so that the route may be changed and another signal, such as signal RC2 35 may be cleared. It is understood that, although not shown in detail in the drawing, the switch 40 mechanism 2M is controlled by the approach locking relays R2MR and L2MR in the usual and well-known manner so that the switch 2 can not be operated if either of these relays is released.

It will be readily apparent how the signal control relays RC2H and RD2H operate to cause the signals RC2 and RD2 to control traffic moving from the track Y to the stretch X, since these relays are controlled in a manner similar to that just described for the signal control relays RA2H 45 and RB2H. Likewise, it is obvious how the relays LA2H and LB2H are controlled by relay L2HS for causing the signals LA2 and LB2 to govern traffic moving over the switch 2 in the opposite direction. 50

Although complete circuits and apparatus are shown only for the signals associated with switch 2, it is understood that similar apparatus and circuits are provided for the signals associated with switch 6 at the other end of the manual 55 block section and that such apparatus operates in a manner similar in all respects to that just described for the apparatus associated with switch 2.

Although I have herein shown and described 60 only one form of apparatus embodying my invention, it is understood that various changes and modifications may be made therein within the scope of the appended claims without departing from the spirit and scope of my invention. 65

Having thus described my invention, what I claim is:

1. In combination, a stretch of railway track divided into a plurality of track sections, a first 70

and second signal for governing eastbound traffic through said stretch, another signal for governing westbound traffic through said stretch, means for clearing said first signal provided said stretch is unoccupied and said other signal is in its stop condition, a timing device, means for initiating the operation of said timing device after a train has entered said stretch in response to the clearing of said first signal and has vacated a given section of said stretch, and means for clearing said second signal effective only if the remaining portion of said stretch is still occupied by such train when said timing device completes its operation.

15. 2. In combination, a stretch of railway track, a first signal for governing movement of traffic through said stretch in one direction, a second signal for governing movement of traffic through said stretch in the same direction, another signal for governing movement of traffic through said stretch in the opposite direction, a normally deenergized signal control relay for governing said first and said second signals, means effective to clear said first signal when said signal control relay is energized provided said stretch is unoccupied and said other signal is in its stop condition, and means including a timing device for automatically clearing said second signal a predetermined time interval after a given section 25 of said stretch becomes unoccupied by a train provided said signal control relay is then energized and the remaining portion of said stretch is then occupied by such train.

3. In combination, a stretch of railway track including a plurality of track sections, a signal for said stretch, a time element relay, means for initiating the operation of said time element relay when a train entering said stretch has vacated a given section of the stretch, and means effective while the remaining portion of said stretch is occupied by such train to prevent said signal from displaying a proceed indication until said time element relay completes its operation.

4. In combination, a stretch of railway track including a switch, a plurality of signals for governing traffic movement over said switch in one and in the other direction, approach locking apparatus for said signals, a timing device controlled by traffic conditions in said stretch for at 45 times governing said approach locking apparatus, and means also governed by said timing device for at other times causing the signals governing movements of traffic over said switch to be effective for enforcing a time interval between 50 trains following one another in such one direction.

5. In combination, a stretch of railway track including a manual block section, a traffic relay controlled by traffic conditions in said block, a 60 timing device controlled by said traffic relay, and means controlled jointly by said traffic relay and said timing device for enforcing time spacing between trains following one another into said block while said block is occupied.

65. 6. In combination, a stretch of railway track including a detector section and a plurality of other sections each having a track circuit including a track relay, a traffic relay controlled in part by all of the track relays of said other 70 sections, a signal for said stretch, a signal control relay for said signal, a stick relay, a pick-up circuit for said stick relay including a front contact of said traffic relay and a back contact of said track relay for the detector section as 75 well as a front contact of said signal control

relay, a first stick circuit for said stick relay including its own front contact and a back contact of the track relay for the detector section as well as a front contact of said traffic relay, a second stick circuit for said stick relay including its own front contact and a back contact of said signal control relay as well as a back contact of said traffic relay, another signal for said stretch, another signal control relay for controlling said other signal, and means controlled by said stick relay for at times energizing said other signal control relay a measured time interval after the rear of a train entering said stretch departs from said detector section.

7. In combination, a stretch of railway track including a detector section having a track circuit including a track relay, a signal for said stretch, a signal control relay for said signal, a traffic relay for said stretch, a directional stick relay controlled by said traffic relay and by said signal control relay as well as by said track relay, an approach locking relay for said signal, a slow pick-up relay, a first operating circuit for said slow pick-up relay including a back contact of the signal control relay and a back contact of the approach locking relay as well as a back contact of the directional stick relay, a second operating circuit for said slow pick-up relay including a back contact of the signal control relay and a back contact of the traffic relay as well as a front contact of the track relay and a front contact of the stick relay, another signal for said stretch, another signal control relay for said other signal, and means controlled by said slow pick-up relay for at times energizing said other signal control relay.

8. In combination, a stretch of railway track, a normally energized traffic relay for said stretch, means for deenergizing said traffic relay when a particular portion of said stretch is occupied by a train, a timing device, means for at times initiating the operation of said timing device when said traffic relay is deenergized, a normally deenergized signal control relay, and means for at times energizing said signal control relay effective when said timing device completes its 40 operation provided said traffic relay is then deenergized, and a signal for said stretch controlled by said signal control relay.

9. In combination, a stretch of railway track, a normally energized traffic relay for said stretch, means for deenergizing said traffic relay when a particular portion of said stretch is occupied by a train, a normally deenergized time element relay, means for at times initiating the 50 operation of said time element relay effective when said traffic relay is deenergized, a normally deenergized repeating relay for said time element relay, means for energizing said repeating relay when said time element relay completes its operation, a first signal control relay, a circuit for said first signal control relay including a front contact of said traffic relay, a second signal control relay, a circuit for said second signal control relay including a back contact of said traffic relay and a front contact of said repeating relay, and a first and second signal for governing traffic through said stretch controlled by said first and second signal control relays respectively.

10. In combination, a stretch of railway track including a switch, one signal for governing movement of traffic over said switch in one position, another signal for governing movement of traffic over said switch in the other position, a timing device, means for at times initiating 70

the operation of said timing device when said stretch is occupied by a train, and means for clearing such one signal or such other signal in accordance with said one or said other switch position respectively, provided said stretch is occupied by the train when said timing device completes its operation.

11. In combination, a stretch of railway track including a manual block section, signal means at the entrance to said block section, a normally deenergized directional relay, means effective

when said relay is energized to cause said signal means to display one indication provided said block is unoccupied, a timing device, means for at times initiating the operation of said timing device when said block is occupied by a train, and means for causing said signal means to automatically display a different indication effective when said timing device completes its operation provided said block is then occupied by such train and said directional relay is then energized. 5 10

HARRY C. VANTASSEL.
